UNITED STATES PATENT OFFICE.

ELZIE L. RIDGWAY, OF EXCELSIOR SPRINGS, MISSOURI.

IRONING-BOARD.

1,150,826.

Specification of Letters Patent. Patented Aug. 17, 1915.

Application filed June 16, 1915. Serial No. 34,515.

To all whom it may concern:

Be it known that I, ELZIE L. RIDGWAY, a citizen of the United States, residing at Excelsior Springs, in the county of Clay 5 and State of Missouri, have invented a certain new and useful Improvement in Ironing Boards, of which the following is a specification.

My invention relates to improvements in ironing boards.

The object of my invention is to provide an ironing board with novel supporting means, which, when the board is not in use may be collapsed to compact space, and 15 which, when extended may support the board firmly in the operative position.

Another object of my invention is to provide a combined ironing board and clothes rack, the latter being adapted to support the clothes after they have been ironed, and 20 arranged to be swung to a collapsed position upon one side of the board when not in use.

Still another object of my invention is to 25 provide an ironing board with a water receptacle pivoted thereto so as to be swung to and from a position in which the board will serve as a cover for the receptacle.

Another object of my invention is to 30 provide an ironing board with a detachable clamp having a sleeve board and a leg pivoted thereto and adapted to be removed from the board with the sleeve board and leg when it is desired to dispense with the 35 leg and sleeve board for any purpose, or to enable a cloth cover to be applied to the board, the clamp serving further, when desired, to assist in securing the cloth cover to the board.

My invention further provides a construction in which all the parts may be disposed in a collapsed position when the board is not 40 in use.

The novel features of my invention are 45 hereinafter fully described and claimed.

In the accompanying drawing, which 50 illustrates the preferred embodiment of my invention, Figure 1 is a perspective view of my improved ironing board shown in the extended operative position. Fig. 2 is a plan view of the same collapsed. Fig. 3 is a vertical longitudinal sectional view of a portion of the ironing board and parts connected therewith shown in the extended position.

Similar reference characters designate similar parts in the different views.

1 designates the ironing board having hinged to its under side a pair of legs 2, which are connected with each other by a cross brace 3, and having, preferably a supplemental bracing bar 4 secured thereto and adapted, when the legs are in the extended position, shown in Figs. 1 and 3 to rest against the board 1.

5 is a U-shaped clamp adapted to embrace the upper and lower sides and one end of the board 1, and provided with two clamping screws 6 adapted to bear against the under side of the board 1.

The inner and upper side of the clamp 5 may be provided with pointed projections 7 for enabling the clamp to be more securely fastened to the board.

The clamp 5 is provided with two downwardly extending ears 8 between and to which is pivoted a longitudinal leg 9 having on its upper side a top plate 10 provided with a transverse notch 11 adapted to receive the brace 3 for holding the legs 9 and 2 in the extended operative position.

A sleeve board 12 has secured to it a U shaped member 13 the arms of which are respectively pivoted to two horizontally extending parallel ears 14 with which the 85 clamp 5 is provided. The sleeve board is also provided with a leg 15 adapted to rest upon the top of the board 1.

A water receptacle comprising a cup 16 is 90 provided with a lateral arm 17 which is pivoted to the under side of the board 1 by a screw 18. The cup may be swung to and from a position under the board 1, in which position the board serves as a cover for the cup. When the cup is in use it is swung 95 to the position shown in Fig. 1.

Secured to the under side of the board 1 is a U-shaped member 19 upon which are adapted to rest a plurality of clothes supporting members 20, each pivoted independently to the under side of the board 1 and adapted to swing between the member 19 and the board 1 to positions extending laterally from one side edge of the board 1, as shown in Fig. 1, or adapted to be swung wholly under the board 1 to the position shown in Fig. 2.

When the board is to be used the sleeve board 12, cup 16 and members 20 may be swung to the operative position shown in 110

Fig. 1. The legs 2 and 9 may be swung to the positions shown in Fig. 1, with the brace 3 disposed in the notch 11, thereby releasably locking the legs in the extended positions.

For locking the legs 9 and 2 against relative lateral movement with respect to each other, the cross brace 3 is provided with a notch 21 in its lower edge, Fig. 2, which receives the plate 10 when the legs are fixed in the extended locked position shown in Fig. 3.

In the collapsed position, the parts will be as shown in Fig. 2.

15 By loosening the screws 6, the clamp 5, sleeve board 12 and leg 9 may be removed bodily from the ironing board 1.

I do not limit my invention to the structure shown and described, as modifications, 20 within the scope of the appended claims, may be made without departing from the spirit of my invention.

What I claim is:

1. An ironing board, a clamp releasably secured to one end thereof, a pair of legs hinged to the under side of the ironing board, a brace connecting said legs, and a longitudinally disposed leg hinged to said clamp and adapted to extend between said 25 pair of legs and provided in its upper side with a transverse notch adapted to receive said brace, and thereby lock the legs releasably in the extended operative position.

2. An ironing board, a U-shaped clamp 30 adapted to embrace and to be releasably secured to said board at one end thereof and

provided with two downwardly extending ears, a pair of legs hinged to the under side of said ironing board, a longitudinal leg hinged to and between said ears and adapted to extend between said pair of legs, and releasable means for locking the three legs in the operative extended positions.

3. An ironing board, a pair of legs hinged to the under side thereof, a brace connecting said legs and provided with a transverse notch, and a longitudinally disposed leg hinged to the ironing board and adapted to be swung between the legs of said pair and to enter said notch, and provided in its upper side with a transverse notch adapted to receive said brace, whereby the legs may be releasably locked in the extended operative position and held against relative lateral movement when in said position.

4. A clamp adapted to be releasably secured to an ironing board, and provided with means for pivotally supporting a sleeve board, and having means for pivotally supporting one leg of an ironing 60 table.

5. A clamp adapted to be releasably secured to an ironing board, and provided with two ears extending at right angles to each other and having means for pivotally supporting a sleeve board upon one of said ears, and having means for pivotally supporting one leg of an ironing table upon the other of said ears.

In testimony whereof I have signed my name to this specification.

ELZIE L. RIDGWAY.
